PRINTING-TELEGRAPH SYSTEM.

1,367,735.

Specification of Letters Patent.

Patented Feb. 8, 1921.

Application filed August 1, 1917. Serial No. 183,891.

To all whom it may concern:

Be it known that I, AMOS F. DIXON, a citizen of the United States, residing at Newark, in the county of Essex and State of

5 New Jersey, have invented certain new and useful Improvements in Printing-Telegraph Systems, of which the following is a full, clear, concise, and exact description.

This invention relates to printing telegraph systems, and more particularly it relates to a transmitting system of the type wherein selecting switch mechanism whose function it is to determine the character of impulses to be transmitted, coöperates with a 10 distributing mechanism, which determines the order of transmission of such impulses, to send out various permutations of signaling impulses to operate suitable printing mechanism at another station.

15 The invention is of particular utility in what is known as single channel operation, as distinguished from multiplex operation. In quadruplex operation, for example, each transmitting set has control of the line for a quarter of the time only. After one transmitting set has, therefore, sent its train of impulses to the line, there remains sufficient time before the line again comes within the control of that set, to readjust the selecting 20 switch mechanism for the sending of a new train of impulses. In single channel operation, however, no such time interval is available and it becomes necessary, in order that the line may be operated at maximum efficiency, that some means be provided for permitting the readjustment of the transmitting set for a new train of impulses before the preceding train has been fully transmitted. In other words, some form of overlap is necessary. Such an arrangement is 25 provided by the present invention.

Between the selecting switch mechanism, which determines the character of impulses to be transmitted, and the transmitting distributor, which determines the order of transmission of these impulses, there is inserted a series of overlap relays whose function it is to store up the signal selected by the selecting switches and permit the readjustment of the selecting switches for a new selection before the transmission of the preceding signal has been completed.

These relays are alternately placed under the control of and locked against control by 30 the selecting switches through a suitable ar-

angement of contacts on the transmitting distributor, whereby the various operations are properly timed to effect the desired result.

In combination with the above feature, 60 this invention makes use of an improved adaptation of the synchronizing system disclosed in my application Serial No. 869,784, filed November 2, 1914, and issued as Patent No. 1,280,423, Oct. 1, 1918. This synchronizing system provides that the polarities of the marking and spacing impulses shall be reversed with each successive transmission of a train of impulses. In other words, if in the first train of impulses the marking impulses are of positive polarity and the spacing impulses are of negative polarity, in the next succeeding train of impulses the marking impulses will be of negative polarity and the spacing impulses of positive polarity. 70 Such an arrangement is of advantage during such period as the transmitting apparatus may be running idle. During such period spacing impulses alone are sent to the line. If these impulses are of alternating 75 polarity a means is available for maintaining synchronism between the transmitter and receiving distributors at all times.

In the particular arrangement herein described, the transmitting distributor employed is of the rotary type and has two sets of transmitting segments, both sets, however, being arranged to transmit the impulses set up by a single set of selecting switches. The overlap relays above mentioned have 80 under their control two sets of pole-changers, one set being connected to one set of transmitting segments of the distributor and the other set being connected to the other set of transmitting segments of the 85 distributor, and each relay having control of one pole-changer of each set. One set of pole-changers is normally arranged to send negative impulses to the line and the other set is normally arranged to send positive impulses to the line. When any overlap relay is actuated it reverses the polarity of both of the pole-changer switches under its control and will, therefore, function to send to the line an impulse of a polarity opposite to that of the spacing impulse, regardless of whether the brush arm of the distributor is traveling over one set of distributor contacts or over the other set of distributor contacts.

The invention will be more clearly understood by reference to the accompanying drawing, in which the contacts of a rotary distributor are shown in extended form at 5 2, 3, 4, 5, 6 and 7 represent the selecting switches commonly associated with an automatic transmitter operated by perforated tape. Associated with these selecting switches are the overlap relays 8, 9, 10, 11 10 and 12 whose circuits are respectively under the control of the selecting switches 3, 4, 5, 6 and 7. These relays have under their control two sets of pole-changers, one set 13, 14, 15, 16 and 17 being connected to the 15 transmitting segments 23, 24, 25, 26 and 27 on one-half of the distributor face, and the other set 28, 29, 30, 31 and 32 being connected to the segments 33, 34, 35, 36 and 37 on the other half of the distributor. It will 20 be noted that the pole-changers 13, 14, 15, 16 and 17 are normally in position to send negative impulses to the line, while the pole-changers 28, 29, 30, 31 and 32 are normally in position to send positive impulses to the 25 line. Each of these pole-changers reverses the polarity sent to the line when the relay controlling it is operated.

To more clearly understand the operation of the system, let us consider that a series of impulses corresponding to the letter Y is to be transmitted. In this case switches 3, 5 and 7 will be actuated and their respective contacts 38, 39 and 40 will be closed. The closure of contact 38 closes 30 circuit from grounded battery 41, through relay 8, to ground, thereby operating both of the pole-changers 13 and 28. As the distributor brush 42 travels over segment 23 a positive impulse from the pole-changer 13 35 will be transmitted by way of the bar 43 to line 44. When brush 42 is in position on segment 23, brush 45 will close the circuit from grounded battery 46, by way of bar 47 to segment 48, thence by way of wire 49 40 to relay 50, and ground. This causes relay 50 to operate, thereby closing contact 51 and completing a circuit from grounded battery 52, by way of wire 53, contact 39 of switch 5, winding 54 of relay 10 to ground. Relay 45 45 50 operates, putting positive potential on segment 25, through the actuation of pole-changer contact 15. As the brush arms 42 and 45 leave their respective segments 23 and 48 relay 50 will be deenergized, closing 50 contact 56 and completing a holding circuit from battery 52 over wire 57 through the 55 operated contact 58 of relay 10 and holding winding 60, to ground. Simultaneously with the operation of relay 10, relay 12 will 60 have been operated by current from grounded battery 52, by way of contact 51, wire 53, contact 40, winding 61, to ground, and will have locked up simultaneously with relay 10 through the closure of the contact 56 upon 65 the deenergization of relay 50. As the brush

42 moves on to the segment 24 a negative impulse will be sent to line from the pole-changer 14, inasmuch as the switch 4, and consequently relay 9, has not been operated. As the brush 42 reaches segment 25 a positive impulse will be sent to the line, due to the fact that, as we have already seen, pole-changer 15 has been operated by the energization of relay 10. As the brush 42 reaches segment 26 the negative impulses 70 will be sent to line, due to the fact that switch 6 and relay 11 have not been operated. At this time, however, brush 45 will connect battery 46 to segment 62, causing the energization of the transmitter magnet 80 63, whose function it is to move the transmitting tape along one step in order to present a new row of perforations to the selecting fingers (not shown) which act in the well-known way to control the contacts of 85 the switches 3, 4, 5, 6 and 7. The setting up of a new selection on the selecting switches does not, however, affect the impulses being sent out by segment 26, nor the one to be sent out by segment 27, inasmuch as the 90 relays 10, 11 and 12, in so far as they have been actuated, are locked in their actuated positions. Thus, when the brush 42 reaches segment 27 a positive impulse will be sent to the line from the pole-changer 17. The 95 brushes 42, 45 now move on the second set of transmitting segments, and if we are to consider that the same letter Y is to be repeated, it will be seen that as brush 42 moves on to segment 33, a negative impulse will 100 be sent to the line from the pole-changer 28; that as the brush reaches segment 34 a positive impulse will be sent to the line from pole-changer 29; at 35 a negative impulse will be sent to the line from pole-changer 30; at 36 a positive impulse from pole-changer 21 and at 37 a negative impulse from pole-changer 32. The preparation of 105 the circuit for the relays 10, 11 and 12 upon the transmission of the first impulse of the series occurs when brush 45 passes over segment 64, and the operation of the transmitter magnet 63 occurs when the brush 45 passes over segment 65 in a manner similar 110 to that described in connection with the first set of transmitter segments. While the segments 62 and 65 which control the resetting of the transmitter are here placed so as to cause this resetting at the time the fourth impulse is being transmitted to the line, it is, of course, evident that this resetting need not take place exactly in coincidence with the transmission of the fourth impulse, the only requirement being that the resetting 115 take place a sufficient time ahead of the transmission of the fifth impulse to insure that the transmitter is reset before the brush 21 moves on to the first segment of the next succeeding series, that is, segment 33 or 23, as the case may be. No locking windings 120 125 130

have been provided for the relays 8 and 9, inasmuch as it has been found advisable to arrange that these relays be operated immediately upon the selection of their respective switches 3 and 4, to prevent the possible mutilation of signals due to lag of relay 50, and furthermore it has been found that sufficient time is available during the transmission of the third, fourth and fifth impulse 10 for the complete resetting of the transmitter.

In the drawing a switch 66 is shown for disconnecting the line 44 from the transmitting distributor bar 43 and connecting it to ground for receiving purposes. The receiving apparatus is indicated at 67 and the receiving segments and brushes of the distributor at 68. This receiving arrangement will not be described further, inasmuch as it 20 is the subject of another application.

What is claimed is:

1. In a printing telegraph system, a plurality of electromagnets, a pole-changer individual to each of said electromagnets, a distributor for successively connecting said pole-changers to the line, selective switching mechanism comprising a plurality of switch members for preparing circuits to said electromagnets, and means under the control of 25 said distributor for closing said circuits.

2. In a printing telegraph system, a plurality of pole-changers, a distributor for successively connecting said pole-changers to the line, selective switch mechanism comprising a plurality of switch members, and means under the joint control of said distributor and said switch mechanism for selectively operating said pole-changers.

3. In a printing telegraph system, a plurality of pole-changers, a distributor for successively connecting said pole-changers to the line, selective switch mechanism comprising a plurality of switch members, and means under the joint control of said distributor and said switch mechanism for selectively operating said pole-changers, and locking said operated pole-changers in their operated positions.

4. In a printing telegraph system, a series 50 of selecting switches, an electromagnet individual to each of said switches and selectively responsive to the actuation thereof, a pole-changer under the control of each of said electromagnets, a distributor for successively connecting said pole-changers to the line, and means under the control of said distributor for releasing said selecting switches for a new selection before the preceding set of impulses selected thereby has 55 been fully transmitted.

5. In a printing telegraph system, a series 60 of selecting switches, an electromagnet under the control of each of said switches, a pole-changer individual to each of said electromagnets and operable thereby to deter-

mine the character of impulses to be transmitted, a distributor for successively connecting said pole-changers to the line, and means under the control of said distributor for completing the circuit of certain of said 70 electromagnets.

6. In a printing telegraph system, a series of selecting switches, a group of pole-changers selectively operable thereby, a distributor for successively connecting said pole-changer 75 to the line, and means under the control of said distributor for locking certain of said pole-changers in their selected position.

7. In a printing telegraph system, a distributor having two sets of switch contacts, 80 a set of pole changers for each set of switch contacts, and switching means simultaneously controlling the operation of predetermined ones of both sets of pole changers.

8. In a printing telegraph system, a rotary distributor having a plurality of groups of transmitting segments, a set of pole-changers individual to each group, and a common switching mechanism for selectively operating corresponding pole-chang- 85 ers of said sets simultaneously.

9. In a printing telegraph system, a distributor having a plurality of groups of transmitting switch contacts, a set of pole changers for each of said groups, and a set 95 of electromagnets for selectively operating predetermined pole-changers of both sets simultaneously.

10. In a printing telegraph system, a rotary distributor having two groups of transmitting segments, a set of pole-changers for each of said groups, a set of electromagnets for controlling pole-changers of both sets simultaneously, and switching mechanism for selectively operating said electro-mag- 100 nets.

11. In a printing telegraph system, a distributor having two groups of transmitting contacts, a set of pole-changers for each of said groups and normally arranged to impress opposite polarities on their respective groups, and means common to both sets of pole-changers for selectively and simultaneously reversing predetermined pole-changers of said sets.

12. In a printing telegraph system, the combination of a distributor adapted to transmit a series of impulses to a line and having a plurality of contacts, means for putting potential on selected contacts, a switching mechanism for actuating said means, means under the control of the distributor and the switching means for locking said means, and other means under the control of the distributor for releasing said mechanism for a new operation before all the pulses of a series have been transmitted to the line by the distributor.

13. In a printing telegraph system, the combination of a distributor adapted to 130

4
transmit a series of pulses to a line and having a plurality of contacts, a plurality of magnets for putting potential on selected contacts, a plurality of selective switching 5 keys for actuating said magnets, means under the control of the distributor for the switching keys for locking certain of said magnets, and other means under the control of the distributor for releasing said 10 switching keys for a new operation before all the pulses of a series have been transmitted to the line by the distributor.

14. In a printing telegraph system, the combination of a distributor adapted to transmit a series of pulses to a line and having a plurality of contacts, a plurality of magnets for putting potential on selected contacts, a plurality of selective switching 15 keys for actuating said magnets, a locking magnet in circuit with and adapted to be energized by the distributor to lock up certain of said magnets, the magnets locked up being dependent upon the selective operation 20 of the distributor and the switching

keys, and other means under the control of 25 the distributor for releasing said switching keys for a new operation before all the pulses of a series have been transmitted to the line by the distributor.

15. In a printing telegraph system, the 30 combination of a distributor adapted to transmit a series of pulses to a line and having a plurality of contacts, a plurality of magnets for putting potential on selected contacts, a plurality of selective switching 35 keys for actuating said magnets, means under the control of the distributor and the switching keys for locking certain of said magnets, and a release magnet adapted to be operated by said distributor at a predetermined moment to release said switching keys for a new operation before all the pulses of the series have been transmitted to the line by the distributor.

In witness whereof I hereunto subscribe 40 my name this 30th day of July, A. D. 1917.

AMOS F. DIXON.
